(57) **CLAIM**

The ornamental design for an audio recorder enclosure, as shown and described.

DESCRIPTION

FIG. 1 is a front perspective view of an audio recorder enclosure showing the design;

FIG. 2 is a back perspective view thereof;

FIG. 3 is a top plan view thereof;

FIG. 4 is a bottom plan view thereof;

FIG. 5 is a front elevational view thereof;

FIG. 6 is a back elevational view thereof;

FIG. 7 is a right side elevational view thereof; and,

FIG. 8 is a left side elevational view thereof.

The broken lines shown in the figures are for environmental purposes only and form no part of the claimed design.
